REINFORCED-CONCRETE PAVING.

Application filed August 31, 1925. Serial No. 53,542.

My invention relates to paving, and more especially to paving of concrete, laid in place preferably in slabs upon a prepared sub-grade, and generally requiring the employment of reenforcing material imbedded in the concrete. My invention relates, further, to the method of paving by means of which the necessity for the employment of reenforcing material, the kind of reenforcing material, and its location in the slab, may be determined in accordance with sub-grade conditions and traffic to be expected, whereby the concrete may be laid in such manner and in such forms, and with the reenforcing materials (if required or employed) so disposed therein as to effect the most economical use of the concrete and reenforcing material, based on sub-grade and traffic conditions, and resulting in the production of a pavement which throughout its length is uniform in its bearing power, notwithstanding varying conditions of sub-grade and traffic to be expected.

Considered chiefly as applied to reenforced concrete paving (although pavement without reenforcement may be laid in accordance with the principles of this invention, as will be apparent as the description progresses), my invention relates to such paving and to the process of laying the same which consists in laying the concrete and disposing the reenforcement therein in direct relation to the observed or calculated bearing power of the sub-grade at any particular point, as will be more fully apparent from a study of the following specification, including the drawings, and of the appended claims.

The laying of concrete paving, to resist the stresses it is designed to withstand, has been largely a matter of guesswork. It has been laid in thick slabs, often of uniform thickness through its width and length, such as were considered sufficient to withstand the maximum stresses without breaking down, and without reenforcement. No account was taken of the bearing power of the sub-grade upon which the concrete was laid, and which in a pavement of any considerable length is bound to vary, with the result that for sub-grades of high bearing power, the excess thickness of the concrete (and often the

preparation of such a hard sub-grade for the reception of the concrete) entailed considerable wastage, even though the thickness 55 might be decreased for sub-grades of known high bearing power, if laid of uniform thickness through its width the excess thickness at points in the width where the stresses are a minimum, entailed a wastage. 60

To avoid wastage of the class mentioned, it has been proposed to incorporate reenforcing matter in the concrete. Through lack of knowledge of the bearing power of the sub-grade beneath the several portions 65 of the paving, and further by reason of the necessity of making the paving as nearly as possible uniform, due to the unskilled labor employed in laying it, the use of reinforcement in concrete paving has been 70 done in much the same manner as the laying of such pavement without reenforcement, that is, without regard to the bearing power of the sub-grade or the value of stresses in the several portions of the paving in determining the sizes or location of the reenforcing materials. Steel is recognized as being 75 of far greater strength in tension than concrete, and hence where tension is found it is desirable to use steel. However, the steel 80 which has been employed has been put in largely as a matter of guesswork; if steel of a given concentration and strength, placed at a certain point did not cure defects in the roadway, it was tried at other points, or 85 with different arrangements or concentrations. It was used, thus, uneconomically, primarily because of lack of knowledge of a better method or system of obtaining the desired results, namely, a paving surface sufficiently strong to carry the traffic loads. 90

Generally the reenforcing materials have been equally spaced throughout the paving slabs, both laterally and longitudinally, and often of uniform strength throughout. 95 While the use of reenforcement may avoid wastage of concrete, its indiscriminate use, as heretofore employed, entails an obvious wastage of the reenforcement.

Data relative to stresses applied to and 100 existing in concrete roads with respect to traffic and with respect to the effect of a given sub-grade, has been made available through publication from time to time of

the results of tests conducted by the United States Bureau of Public Roads, at Arlington, Virginia, and by the State of Illinois on the Bates road. Later data from the same source, and tests conducted by the California State Highway Commission at Pittsburgh, California, gives the distribution of the load on the sub-grade with the central load on the slab. Reference to all of these tests will show, however, that they have done no more than to give the results of certain specific experiments as to the results obtained by tests under certain specific conditions and on certain specific pavings. They enable the engineer to determine by experiment on any special paving after it is laid, of varying sub-grade and traffic conditions, and they point out to him the result of varying sub-grades and traffic conditions upon the specific paving tested, but they do not point to any system whereby the engineer can calculate beforehand what will be the effect upon the paving he proposes to lay, of the existing sub-grade and expected traffic conditions, nor do they enable him to see when reenforcing is required, nor of what character and strength, or where it is to be placed in the slab. These tests will indicate to the engineer, generally, when reenforcing of some kind is required, but he is still confronted with the problem of designing his pavement to care for the sub-grade conditions which may exist at any particular point in his paving, and of determining where the reenforcement is to be placed in the slab, and of what strength and character it is to be.

My method is concerned with the determination of the character of paving to be employed, and the character and positioning of the reenforcement to be required, if any, in the paving slabs, starting with the results of the experiments mentioned, as a basis. According to my method, therefore, I employ reenforcing material at such points and in such manner and of such strength as to resist stresses which can be foreseen through observation of the bearing power of the sub-grade and through calculation of the probable stresses due to the passage of loads over the pavement, eliminating the reenforcing material where the stresses to be expected and the reaction of the sub-grade, render it unnecessary, and I so form the concrete slabs as to most effectively resist the same stresses, thus effecting an economy of concrete materials, reenforcing materials, and labor, and producing a cheaper and better pavement without requiring the use of more skilled labor in the laying of the paving.

My invention will be best understood by reference to the accompanying drawings, wherein I have illustrated my method of paving and reenforcement therefor, constructed in furtherance of my method and

according to my invention, in which Figure 1 is a diagram illustrating an application of the method for determining the reenforcement to be employed.

Figure 2 is a perspective view of the re-enforcing for a single paving slab, extending over the full width of the road.

Figures 3 and 4 are sections longitudinally of the slab on the respective lines 3—3 and 4—4 of Figure 2.

Figures 5 and 6 are sections transversely of the slab along the respective lines 5—5 and 6—6 of Figure 2.

Figure 7 is a plan view of a slab designed for a road with a center joint.

Figures 8 and 9 are sections longitudinally of the road on the respective lines 8—8 and 9—9 of Figure 7, and Figures 10 and 11 are sections transversely of the slab, along the respective lines 10—10 and 11—11 of Figure 7.

Certain assumptions are necessary and can be accepted as proven by experience, and by the results of the tests mentioned above, as a basis for my method of design. These are as follows: (1), that the sub-grade is uniformly elastic up to the limit of the bearing power used, (2), that the sub-grade bearing power is as determined by using a bearing block at least five square feet in area, and is the reaction obtained when the deflection of the sub-grade is 0.12 inch under the point of application of the load, (3), that the elastic curve of the loaded slab is shaped as determined by the Arlington experiments, (4), that half of the load is carried by the sub-grade between the points of contraflexure of the elastic curve when the slab is loaded at the edge, (5), that when there is a sudden change from a hot to a cold atmosphere, the corners of the slab curl up so as to receive no support from the sub-grade at all. These assumptions are all well founded on experience, as has been noted.

There is one more assumption which may be said to be still in a slightly experimental stage, and which can be called assumption (6). It is that when the central portion of the slab is designed with a thickness corresponding to that generally found necessary in accordance with the Arlington experiments, all failures will be at the corners or will start at the edges. The result of this assumption is that reenforcing bars in the middle are only required for the purpose of distributing stresses, as, for example, temperature stresses, and taking care of moments caused by unintentional local settlement of the sub-grade. Further reenforcement in the center of the slab, is non-essential, nor is it even desirable, contrary to ordinarily accepted practice.

My method has been employed in designing the reenforcement placed in a concrete road in King County, Washington, known

as the Renton-Maple Valley road, wherein stretches rendered difficult by the character of the subgrade were selected to test the soundness of my method of design and the 5 value of the reinforcement. This road has now been laid and in use some ten months, and no failure is observed. It was laid on fresh fills and where drainage conditions and subgrade conditions were particularly 10 bad because of the presence of large quantities of water and a particularly boggy subsoil. For the purpose of illustrating my method I will give the figures employed there, it being understood of course that 15 these are given for purposes of illustration only, and it is not to be understood that these precise figures are in any sense restrictive. They are given solely for the purpose of illustrating, by reference to an actual 20 construction, how my method is carried out and the results in the form of the reenforcing steel necessary, and its positioning.

On the reenforced sections of this Renton-Maple Valley road the procedure was as follows. The sub-grade, after being prepared, 25 was measured for its bearing power. This was done by placing upon it a slab of not less than five square feet area, and loading this slab until the deflection of the sub-grade was 0.12 inch. This can be done by 30 such instruments as are found suitable and Figure 1 illustrates an elementary form of apparatus which might be employed for the purpose. Therein a loaded truck W is 35 shown upon the roadway, but partially supported by a hydraulic jack J controlled by a pump P , having a gage G by means of which pump a load (the truck) can be applied to the sub-grade through the five square foot 40 slab S and jack J , resting thereupon. The load on the sub-grade through the slab S is increased until the deflection of the sub-grade is 0.12 inch. The deflection can be 45 observed and measured through a scale or scales A , observed through a theodolite T , or like instrument. If two squares A are employed they will compensate for irregularities in the surface or for local variations 50 in the bearing power of the sub-grade or for compression of the materials of the jack itself or the slab S . The observation through a theodolite from a distance will likewise prevent local settling of the sub-grade 55 or like disturbances caused by the placing of the load on the jack, from disturbing the accuracy of the reading.

At one point in the Renton-Maple Valley road, referred to, the bearing power as thus measured, for a 0.12 inch deflection of such a five square foot slab, amounted to 900 lbs. per square foot. The axle load for which 60 the road was designed amount to 18,500 lbs. plus fifty per cent for impact. The strength of the concrete in compression was taken at 65 800 lbs. per square inch, and the strength of

the steel, in tension, at 24,000 lbs. per square inch. Employing the chart for the required thickness for centers, from impact tests at Arlington, with the wheel load of 9250 lbs., I found a six and one-half inch slab was sufficient for the central portion of the road. The edges were thickened to nine inches. By measurement it was found to be general for six and one-half inch concrete slab, where there is 0.12 inch deflection under the load, 70 there is an 0.10 inch deflection at the point of contraflexure of the elastic curve. This fact might be calculated, but calculations of this type are long and laborious and have never yet been accomplished and the result is more easily obtained, well within the limits of accuracy required, by means of actually measuring the elastic curves, as mentioned above. Thus if a load is such as to deflect the slab 0.12 inches under the point of application of the load at the point of contraflexure of the elastic curve the deflection can be assumed as exactly 0.10 inch. 75 Ten-twelfths of 900 lbs. equals 750 lbs. which is the sub-grade bearing at the point of contraflexure (see assumption 1).

$$\frac{900 + 750}{2} = 825 \text{ lbs.}$$

per square foot, which is the average sub-grade bearing between points of contraflexure, for soil having a 900 lbs. per square foot bearing power. 95

$$\frac{(9250)1.5}{2} = 6937.5 \text{ lbs.}$$

required to be supported by the pavement between the point of contraflexure; that is 100 6937.5 lbs. must be carried by the pavement slab to points beyond the point of contraflexure. To find the distance apart of the 105 points of contraflexure, consider the area (represented by letter A) to be a parabola with its base (represented by letter L), 110 twice as long as its altitude. Then

$$A = 2/3 L \frac{L}{2}, \text{ and } L = \sqrt{3A},$$

but

$$A = \frac{1/2(\text{load} + 50\% \text{ impact})}{\text{average sub-grade bearing}};$$

therefore

$$L = \sqrt{\frac{6937.5(3)}{825}} = 5.02 \text{ ft.} = 60 \text{ inches,}$$

approximately. The maximum moment M will then be as for a simple beam with span 120 L and concentrated load of 6937.5 lbs. 125

$$M = \frac{WL}{4} = \frac{6937.5}{4} 60 = 104,000 \text{ inch lbs.}$$

The longitudinal edge of the slab is now 130

designed as a simple reenforced concrete beam. This is a simple and a somewhat approximate way of obtaining the result, but the whole purpose of the present method is to obtain a system simple enough and accurate enough for general use.

It will be seen that the higher the bearing power of sub-grade the shorter the distance between points of contra-flexure and consequently the smaller the amount of steel required, until we reach the sub-grade that requires no steel at all, in the bottom of the edges of the slab. Reversely, the softer the sub-grade the stiffer must the paving slab be made by means of reenforcement, in accordance with the definite law outlined above. Negative bending moments beyond the point of contraflexure are small in comparison to the positive moments, and usually not in excess of the tensile strength of the concrete. However, to take care of these negative moments in case they should become excessive for any reason by local settlement of the slab, a $\frac{1}{2}$ inch bar is run along the top of the edge. This will be seen at 1 in Figures 2 and 4. This bar 1 also serves to resist stresses which arise through changes in temperature or shrinkage, and which would produce tensional stresses throughout the top of the edge of the slab.

The principal longitudinal bars, it will be seen, are chiefly required at the bottom of the side edges, intermediate the ends of the slab. These are indicated at 2 and 20. The bending moments at the corners, however, will largely be negative, and the ends of these bars would have little effect in resisting compressional stresses thus occurring. However, the ends of the bars must be anchored in the concrete for sufficient bond to enable their central portions to act effectively, and further, the corners are acted upon by moments which produce tensional stresses in their upper portions. Therefore, by bending the ends of the bars upward as shown at 21 and 22, such negative bending moments, occasioned as outlined in assumption 5, are taken care of by the ends, and economy of material is effected. Further, it is possible to stiffen this element of the reenforcing structure, and consequently the entire structure, by tying certain of these bent-up ends to the ends of the bars 1, as indicated at 12. The maximum moment at the corners is a function of the sub-grade and the relative temperature and moisture content of the top and bottom of the slab, but for most practical work with the thickness of slabs usually employed, it may be considered as being at a point two to three and one-half feet distant from the corners. It is here that I have found from experience slabs usually fail.

It may also be desirable to assist in caring for local stresses to extend a bar, as

through the edges of the slab from end to end at its bottom. The position of the bars 2, 20, 1 and 3, that is, as to which is outermost, is to a large extent immaterial, but they should all be fairly close to the edge. For best results, I prefer to space the bars 1 and 2 substantially four inches inward of the edge of the slab, the bar 3 eight inches inward of the edge of the slab, and the bar 20 twelve inches inward of the edge, the total width of the roadway being twenty feet. The object is to place the reenforcing as close as practicable to the edge. If the length of slab in such a roadway is twenty feet, the sections 21 and 22 may be four feet three inches in length, and the bent sections 23 and 24, respectively, may extend through a foot in length, making the sections 2 and 20 nine feet long.

Lateral reenforcement.

This theory of lateral flexure of paving slabs shows that maximum moments, except at corners, occur at the middle of the ends of the slab, and are both positive and negative. The greatest of these are negative, due to the curling up of the edges of the slab, the softening of the sub-grade near the edges of the pavement by saturation with water, and by the action of frost in the center. In the lateral reenforcement I have neglected impact.

For such a twenty-foot pavement as used for illustration, the maximum clear distance apart between the two lines of traffic is considered to be seven feet. The total of the two axial loads in line is 37,000 lbs., of which three-fourths is transmitted to the sub-grade outside of the seven-foot clear distance. The remaining one-fourth, or 9250 lbs., can be considered uniformly distributed on the sub-grade along the seven-foot interval. The resulting moment is

$$\frac{9250(84)}{8} = 97,125 \text{ inch pounds.}$$

The top reenforcement of the edge is accordingly designed under the method described in connection with the longitudinal edge, that is, as a beam. It will be noted that the narrower the pavement the smaller the amount of top lateral reenforcement required. The bottom lateral reenforcement is designed in exactly the same manner as the longitudinal reenforcement, except that the allowance of 50% for impact has been omitted.

I find thus that at the transverse edges of the slab, bars 4, 40, 41 and 42 are required, extending across the slab adjacent its edges and in the upper portion of the slab. Like transverse bars 5 and 50 are employed in the bottom of the slab, the number being less because of the lower value of the positive moments as compared with the negative moments.

ments. The bars 4, 40, 41 and 42, as will be seen in Figure 6, are substantially straight, at least may be left unbent and will conform to the crown of the road as they are connected to the bars 1, 2 and 20. The bars 5 and 50, however, are preferably bent as indicated in Figure 6, to conform to the thickening of the edges of the slab.

To distribute local stresses I prefer to incorporate in the slab, longitudinal bars 6, 60 and 61, placed generally in the bottom of the slab, in accordance with the principles involved in the employment of the bars 2 and 20, although the bar 6 is placed in the center at the top and other like bars may be employed if their use is found desirable. Thus the center of the slab, with the exception of the bars 6, 60, and 61, and with the exception of the transverse bars 7, which are likewise in the bottom of the slab, is free of reenforcement. The bars 6, 60 and 61 and the bars 7, are ordinarily of lighter material than the bars placed at the edges, and heretofore described, their chief function being, as stated, to distribute local stresses and not to resist stresses due to expected sub-grade conditions. The main reenforcing bars 1, 2, 3, 4 and 5, are altogether in or near the edge of the slab, where from experience and by reason of the method outlined above, it appears that they are most required.

Of course it will be understood that the bars may be secured together in any way found suitable or which may be desired, and that spacing means such as the stirrups 8 may be employed to maintain them in proper position until imbedded in concrete. The precise manner of securing the bars together or of spacing them forms no part of my invention.

The same principles may be employed in designing a slab having a center joint, as shown in Figures 7 to 11, inclusive. This differs from the former design chiefly in the inclusion of the bars 2' at the center joint, that is, imbedded in the slab just within the center joint indicated at 9. This is required because of the use of two adjoining slabs so that the design of the central portion, that is, parallel to the center joint, must be in accordance with the principles outlined for the design of the edge of the slab. I prefer, however, that the transverse bars 5 and 50, 4, 41, 42, etc., extend completely through the two half slabs in this form, although each half slab may be formed independently or semi-independently of the other, if desired.

It will not be apparent that I have evolved a method of laying such pavement in accordance with the bearing power of the sub-grade in any particular location. The method, briefly, consists in the determination of the bearing power of the sub-grade,

originally through the use of apparatus similar to that illustrated in Figure 1, but frequently merely as the result of observation and experience, and then the application of the data thus obtained, together with the known strength of the materials to be employed, and the loads to be expected, in simple formulas, by means of which the nature and location of the stresses in the concrete may be determined. With this known, and following the principles outlined herein of treating the edges of the concrete slab as loaded beams, it is a simple engineering feat to determine the strength and number of bars to be employed. Bars of the proper strength and sufficient in number, as calculated by the engineer in charge, are then prepared in forms and tied together as in the illustration of Figure 2, and laid in place on the prepared sub-grade. If in a location where the bearing power is high, certain of the bars, as indicated by the application of the formula and the principles outlined above, as, for example, the bar 3 or the bar 20, may be eliminated. The concrete, of course, is poured about, beneath, and over the reenforcing material, this being suitably supported by any of the well-known means during the process of pouring the concrete.

The method thus outlined and the reenforcement thus designed, provides the maximum resistance to the various stresses occurring in the concrete slab, with the minimum of material, and as noted, provides a means whereby the amount of reenforcement may be calculated and may be varied to suit the conditions at any particular point in the paving.

It will be noted that the joints between bars in the reenforcing structure are tied together, and consequently the entire structure may be set up through the use of proper template forms, either on a portion of the completed paving, or at the side, and then carried as a unit to be laid in place on the prepared sub-grade for the next section to be laid. In this manner there is no delay, there is no tying of the steel bars in place, and the mixer and its crew are never forced to remain idle to enable the positioning or tying of the reenforcing structure.

What I claim as my invention is:

1. A paving slab comprising a monolithic concrete structure including a plurality of reenforcing bars extending from end to end of the slab at its side edges, certain of said bars lying in the lower portion of the slab edge intermediate its ends, and the ends of said bars lying in the upper portion of the slab edge, the remainder of said bars lying wholly in the upper portion of the slab edge, the ends of said latter bars being secured to the ends of the first bars to form a truss-like

structure lying in the side edges of the slab, and said slab, inward of its edges, being largely free of longitudinal reinforcement.

2. Reenforcing for concrete paving slabs comprising longitudinal bars adapted in the main to lie in the lower portion of the side edges of the completed slab, the ends of said bars being bent upwardly and extending longitudinally to the ends of the slab, and adapted to lie in the upper portion of the slab edges, other longitudinal bars adapted to lie wholly in the upper portion of the slab edges, and transverse bars adapted to lie in the end edges and extending from side to side of the slab.

3. Reenforcing for concrete paving slabs comprising longitudinal bars adapted in the main to lie in the lower portion of the side edges of the completed slab, the ends of said bars being bent upwardly and thence outwardly to lie in the upper portion of the slab side edges; other longitudinal bars adapted to lie wholly in the upper portion of the slab edges, and transverse bars adapted to lie in the end edges of the slab when completed, certain of said transverse bars lying in the upper portion of the end edges and the remainder lying in the lower portion thereof.

4. A reenforcing structure for concrete paving slabs comprising longitudinal bars adapted in the main to lie in the lower portion of the side edges of the completed slab, the ends of said bars being bent upwardly and then extending longitudinally to lie in the upper portion of the slab side edges, other longitudinal bars extending from end to end of the side edges at top and bottom, respectively, and transverse bars extending from side to side at the end edges, and positioned at the top and bottom, respectively, stirrups connecting the upper and lower transverse bars, said bent longitudinal bars being connected to the upper and lower longitudinal bars, and said transverse and longitudinal bars being secured together to form a complete, portable structure, transverse bars supported from and secured to the lower portion of said bent bars at opposite sides of the structure, and longitudinal bars extending between and secured to the first-mentioned transverse bars intermediate the sides of the structure.

5. A reenforcing structure for concrete paving slabs comprising longitudinal bars adapted in the main to lie in the lower portion of the side edges of the completed slab, the ends of said bars being bent upwardly and then extending longitudinally to lie in the upper portion of the slab side edges, other longitudinal bars extending from end to end of the side edges at top and bottom, respectively, and transverse bars extending from side to side at the end edges, and positioned at the top and bottom, respectively, stirrups connecting the upper and lower transverse bars, said bent longitudinal bars being connected to the upper and lower longitudinal bars, and said transverse and longitudinal bars being secured together to form a complete, portable structure.

6. A reenforcing element for concrete paving slabs comprising a longitudinal bar adapted in the main to lie in the lower portion of the side edge of the slab, the ends of said bar being bent upwardly and extending to the ends of the slab, and adapted to lie in the upper portion of the side edge thereof, a second longitudinal bar extending between the end portions of said first bar, to lie in the upper portion of the slab edge, and means for securing together the ends of said bars.

Signed at Seattle, King County, Washington, this 24th day of July 1925.

GEORGE D. BURR.
